UNITED STATES PATENT OFFICE.

EMMIT G. LATTA, OF FRIENDSHIP, NEW YORK, ASSIGNOR TO THE POPE MANUFACTURING COMPANY, OF PORTLAND, MAINE.

VELOCIPED-SADDLE.

SPECIFICATION forming part of Letters Patent No. 376,662, dated January 17, 1888.

Application filed January 24, 1887. Serial No. 225,247. (No model.)

To all whom it may concern:

Be it known that I, EMMIT G. LATTA, of Friendship, in the county of Allegany and State of New York, have invented new and 5 useful Improvements in Velocipede-Saddles, of which the following is a specification.

This invention relates to that class of velocipede-saddles which are supported at their front and rear ends, and it has for its object to 10 produce a durable, yielding saddle which is adjustable forwardly or backwardly and vertically, and which can be easily applied to ordinary bicycles.

The invention consists of the improvements, 15 which will be hereinafter fully described, and pointed out in the claims.

In the accompanying drawings, Figure 1 is a longitudinal sectional elevation of a velocipede-saddle provided with my improvements. 20 Fig. 2 is a cross-section in line $y-y$, Fig. 1. Fig. 3 is a fragmentary horizontal section in line $x-x$, Fig. 1. Fig. 4 is a cross-section in line $z-z$, Fig. 1. Fig. 5 is a cross-section in line $w-w$, Fig. 1. Fig. 6 is a side elevation of the 25 support of the rear spring.

Like letters of reference refer to like parts in the several figures.

A represents the backbone or reach; a , the flat neck formed at the front end thereof, and 30 A' the steering-head.

a' represents the transverse hole usually formed in the neck a for the attachment of the ordinary flat spring.

B represents the seat of the saddle, constructed of leather or other flexible material, and provided at its front end with a metallic 35 pommel-plate, b , which is riveted to the under side of the seat and shaped to form a pommel of the desired form. The plate b is constructed 40 with depending side flanges, b' , as represented in Fig. 5.

C represents an upright bar or rod which supports the front end of the saddle and which is pivoted at its lower end to the neck a by a 45 horizontal bolt, c , which passes through the hole a in the neck. This upright bar is preferably constructed from a blank of sheet metal by bending the same so as to form two side pieces, $c' c'$, and a connecting cross-piece, c^2 , 50 arranged above the neck a . The lower portions of the side pieces, c' , straddle the neck

a and are pivoted to the bolt c . The upper portions of the side pieces, c' , are arranged against the inner sides of the depending flanges b' of the plate b , and are pivoted to the latter 55 by a horizontal bolt, c^3 .

D represents the front spring, secured with its upper end to the rear side of the upright bar C and resting with its lower portion upon the backbone A. The upper end of the spring 60 D is secured to the front side of the cross-piece c^2 of the bar C by a horizontal bolt, d , which passes through a vertical slot, d' , in the spring and through the cross-piece c^2 . The nut d^2 of the bolt d and the adjacent side of the spring 65 D are provided with interlocking serrations, as shown in Fig. 1, whereby the spring is securely held in place. Upon loosening the bolt the spring can be raised or lowered on the bar C. By raising or lowering the spring the upper end of the bar C is thrown backwardly or 70 forwardly, whereby the front end of the saddle is adjusted accordingly. This permits the saddle to be readily adjusted to fit any bicycle with inclosed steering-head regardless of the 75 position of the bolt-hole in the neck.

The lower end of the front spring, D, is curved forwardly and upwardly, so as to strike under the upper portion of the spring and render the same comparatively rigid when the 80 spring is subjected to a serious shock, while the spring yields slightly when the machine passes over ordinary obstructions.

E represents the rear spring, composed of two branches, $e e$, which are attached with 85 their upper ends to the saddle and provided at their lower ends with coils $e' e'$, having their convolutions made of decreasing radius toward the frame of the machine. The coils e' are connected by a transverse bow or curved 90 piece, e^2 , which extends across the backbone, as represented in Fig. 2.

F represents the base-plate, which supports the rear spring, E, on the backbone, and which is made concave on its under side and curved 95 lengthwise to fit closely against the upper side of the backbone. The base-plate F is provided at its sides with upwardly-projecting ribs or ledges f , forming seats in which the inner convolutions of the coils e' rest, as represented in 100 Fig. 4.

G represents a transverse clamping plate or

bar extending across the base-plate F and the lower portions of the coils e'.

g represents a clip which embraces the lower side of the backbone and passes, with its legs, 5 through openings in the clamping-plate G, said legs being provided above the clamping-plate with screw-nuts, whereby the clamping-plate is pressed against the spring and base-plate, thereby securing these parts together and to 10 the backbone.

The clamping-plate G is provided on its under side with grooves or concave seats g', in which the coils enter and by which lateral displacement of these parts is prevented.

15 The edges of the base-plate F are notched to hold the legs of the clip in position with reference to the base-plate.

The base-plate F is provided on its upper side in front of the clamping-plate G with two 20 longitudinal ribs, h h, forming a longitudinal groove.

H represents a raised spring support or block seated on the base-plate in the groove between the ribs h and provided with a series 25 of notches, i i' i'' i''', arranged at different heights for supporting the transverse bow e' of the rear spring at varying heights.

When the rear end of the saddle is to be placed in its lowest position, the support H is 30 removed and the bow e' is permitted to rest directly on the base-plate, in which case the base-plate prevents the spring from injuring the backbone. When the saddle is required to be placed in a higher position, the support 35 H is put in place and the bow e' of the spring is placed in the notch in which it will properly support the saddle.

I represents a curved rod or wire secured to the under side of the cantle or rear portion of 40 the saddle near the edge thereof and provided with two horizontal sockets or eyes, i' i'', which are secured to the wire I, by rivets or brazing, on opposite sides of the center line of the saddle.

45 j j represent outwardly-projecting pivots formed at the upper ends of both branches of the rear spring, E, and engaging in the sockets i' i'', into which they are sprung. The wire I, which forms the cantle-frame, is preferably 50 made of spring-temper, and is secured to the seat by a strip of leather which envelops the wire, and is secured to the seat by rivets k. The cantle may, however, be provided with an ordinary metallic frame if preferred.

55 I claim as my invention—

1. The combination, with the frame of a velocipede, of an upright standard pivoted at its lower end to the frame, a saddle, a rigid pommel-plate secured to the saddle, and a horizontal 60 pivot connecting the upper end of the standard to the pommel-plate, substantially as set forth.

2. The combination, with the frame of a velocipede, of an upright standard pivoted at its 65 lower end to the frame, a saddle, a rigid pommel-plate secured to the saddle, a horizontal

pivot connecting the upper end of the standard to the pommel-plate, and a curved metallic spring secured with its upper end to the standard and resting with its curved lower end 70 upon the frame, substantially as set forth.

3. The combination, with the frame and saddle of a velocipede, of an upright supporting-bar pivoted to the frame and saddle and a supporting-spring secured to the supporting- 75 bar and made vertically adjustable thereon, substantially as set forth.

4. The combination, with the frame and saddle of a velocipede, of an upright supporting-bar pivoted to the frame and saddle and composed of side pieces, c', and a connecting cross-piece, c'', a supporting-spring, D, provided in its upper end with a vertical slot, d', and a bolt, d, whereby the spring is adjustably secured to said cross-piece, substantially as set 85 forth.

5. The combination, with the frame and saddle of a velocipede, of a supporting-standard pivoted to the frame and saddle and a supporting-spring secured to said standard and 90 resting on the frame, and having its lower end curved upwardly and adapted to strike the upper portion of the spring when the latter is subjected to an excessive shock, substantially as set forth.

95 6. The combination, with the frame and saddle of a velocipede, of a metallic pommel-plate secured to the under side of the saddle and a supporting-bar pivoted with its upper end to said pommel-plate and with its lower end to the frame, substantially as set forth.

7. The combination, with the backbone of a velocipede and the saddle, of a supporting-spring composed of two coiled branches and a base-plate resting on the backbone and provided with curved seats in which the coils of the spring are supported, substantially as set forth.

105 8. The combination, with the backbone of a velocipede and the saddle, of a supporting-spring composed of two coiled branches, a base-plate resting on the backbone and provided with curved seats for the inner coils of the spring, and a clamping-plate whereby the base-plate and the spring are secured to the 110 backbone, substantially as set forth.

9. The combination, with the backbone of a velocipede and the saddle, of a supporting-spring, a base-plate resting on the backbone, and a detachable supporting-block resting on 115 the base-plate, substantially as set forth.

10. The combination, with the backbone of a velocipede and the saddle, of a supporting-spring, a base-plate resting on the backbone and provided with a longitudinal groove, and a detachable supporting-block arranged in the 120 groove of the base-plate, substantially as set forth.

11. The combination, with the backbone of a velocipede and the saddle, of a supporting-spring, a base-plate resting on the backbone, and a detachable supporting-block resting on 125

the base-plate and provided with a series of seats for the spring at different elevations, substantially as set forth.

12. The combination, with the backbone of a velocipede and the saddle, of a supporting-spring composed of two coiled branches, a base-plate provided on its upper side with curved seats in which the coils of the spring are supported, a clamping-plate provided on its under side with concave seats resting on the coils of the spring, and a clip whereby the clamping-plate is secured to the backbone, substantially as set forth.

13. The combination, with the backbone of a velocipede and the saddle, of a supporting-spring composed of two coiled branches and a saddle-frame composed of a curved round

metallic rod secured to the saddle and connected detachably with the spring, substantially as set forth.

14. The combination, with the backbone of a velocipede and the saddle, of a supporting-spring composed of two coiled branches and a saddle-frame composed of a round metallic rod provided with sockets in which the upper ends of the branches of the spring are inserted, substantially as set forth.

Witness my hand this 14th day of December, 1886.

EMMIT G. LATTA.
